INTERLOCKING SYSTEM FOR RAILROADS

Carl F. Stoltz, Cincinnati, Ohio; Rhuella A. Stoltz,
owner by decree of court, assignor to General
Railway Signal Company, Rochester, N. Y.

Application October 25, 1929, Serial No. 402,527

30 Claims.

(Cl. 246—3)

This invention relates to interlocking plants for railroads, and more particularly pertains to the electrical interlocking between the various traffic controlling functions in such plants.

5 Due to the density of traffic in interlocking plants at certain critical times, the interlocking system used to interrelate the operation of the various traffic controlling functions, must eliminate all possible time delay in order to justify 10 itself economically. This facility in train operation, of course, must be accomplished in a safe and reliable manner.

In accordance with these conditions, interlocking practice has established what is termed 15 as "route locking," that is, a route, composed of any number of track sections, is set up for a train to pass through an interlocking plant which route cannot be changed after a train has accepted the governing signal except under certain 20 predetermined conditions. However, it is desirable, in order to prevent delay, that each of the track sections included within the route shall be obtainable for new routes as soon as the 25 train leaves these sections, and this interlocking feature is termed "sectional route locking."

With the above and other considerations in mind, the present invention proposes to provide 30 an improved sectional route locking system for use in interlocking plants. More specifically, the present invention proposes to provide electric 35 circuits interlocked through relays and the like for interrelating the operation of the various signals, switches, and the like of an interlocking plant. One group of relays and associated circuits are to establish what may be termed as 40 directional routes, that is, certain of the relays are affected only when a route is set up in one direction and certain other of the relays are affected only when a route is set up in the opposite direction. By the interlocking of the signal control 45 circuits with these directional route relays, a train is given head-on protection, or in other words, two routes opposing each other in direction cannot be set up. Another group of relays and circuits are to establish the approach locking 50 for the track switches, which relays and circuits, when combined with the directional route locking relays, provide that a route cannot be taken away from a train after it has been accepted, except under predetermined conditions, and also provide that a particular section shall be released to be used at the will of the operator 55 immediately after becoming unoccupied.

A further object of the invention is to provide 55 means whereby a particular route may be manu-

ally released with the train on the route to allow another train or engine to proceed towards the first train under control of governing signals so that the two trains may be coupled together.

Other objects, purposes and characteristic features of the present invention will be in part obvious from the accompanying drawings, and in part pointed out as the description of the invention progresses.

In describing the invention in detail, reference 10 will be made to the accompanying drawings, in which similar reference characters are used to designate similar devices with each having distinctive exponents that are used to distinguish the group of devices to which the particular device belongs, and in which Figs. 1 and 1A when placed end to end comprise one complete diagrammatic representation of a stretch of railroad track, including track switches and associated signals, as electrically interlocked by the 15 devices and circuits constructed and arranged 20 in accordance with the present invention.

With reference to the accompanying drawings, a stretch of track at the entrance and exit of an interlocking plant is shown as including track 25 sections T^0 , T^2 , T^4 , T^6 , and T^8 , each of which is provided with the usual track battery and track relay (not shown) with the condition of these track sections, as given by the track relays, repeated in the interlocking tower by track repeater relays TR^0 , TR^2 , TR^4 , TR^6 , and TR^8 respectively. It will be noted, that for convenience only the track repeater relay TR^8 has been indicated as governed by the conditions of its respective track section T^8 .

The track section T^2 contains a track switch TS^a which, when reversed, allows the passage of traffic onto a turn-out track section TO^a ; and, similarly the track section T^6 contains a track switch TS^b which, when reversed, allows the passage of traffic onto a turn-out track section TO^b . These track switches TS^a and TS^b are controlled to normal or reverse extreme locked conditions by their respective switch machines SM^a and SM^b .

The east bound traffic over track section T^2 is 45 governed by a dwarf signal S^3 which is of the two indication type for governing low speed routes, while a signal S^7 is a high signal of the three indication type for governing the passage 50 of east bound traffic over the track section T^6 , as this track section is the exit of the interlocking plant and the entrance to high speed automatic block signal territory. A dwarf signal S^9 of the two indication type is provided for governing 55 west bound traffic over the track section T^6 .

Likewise, a dwarf signal S^5 of the two indication type is provided for governing west bound traffic over the track section T^2 .

In the interlocking tower, a miniature track layout, identical in every respect to the actual track layout in the interlocking plant, is provided with track sections t^0, t^2, t^4, t^6 , and t^8 . Also, the turn-out track sections TO^a and TO^b are similarly represented by the turn-out track sections to^a and to^b . The signals governing traffic are represented on the track diagram by the usual signal symbols of which symbols s^3, s^5, s^7 , and s^9 are shown in locations corresponding to the locations of the respective trackway signals. Preferably this miniature track layout should include indicator lights to indicate the occupancy of a particular track section by a train, but which lights have been omitted for the sake of clearness in setting forth the present invention. Indicator lights can also be provided to give the indications displayed by the signals S^3, S^5, S^7 , and S^9 respectively but said lights likewise have been omitted to simplify the disclosure.

Signal levers SL^3, SL^5, SL^7 , and SL^9 are located beneath the symbols which represent the respective signals which they control. These signal levers control contacts which are normally open with the levers SL in normal positions as shown, and which are closed with the levers in right-hand dotted line positions and remain closed until they are manually moved from such positions. Switch machine levers SML^a and SML^b are provided for controlling their respective switch machines SM^a and SM^b by operating their respective contacts to either of two extreme positions which positions are maintained until said levers are manually moved.

A push button PB of the usual self-restoring type is located beneath track section t^4 for releasing the route set up for a train standing on that track section. A time element release TE is provided for manually releasing a time element mechanism to open certain contacts and close certain other contacts a pre-determined time thereafter. This time element operated contact mechanism TEC may be a plunger and valve arrangement as shown, a mechanical clock work device or any other well known mechanical means for accomplishing the result.

50 Lever relays R^3, R^5, R^7 , and R^9 are provided to repeat the condition of the associated signal levers SL . Also, relays SS^a and SS^b are the usual switch repeating relays located in the tower to indicate the position and locked condition of their respective track switches TS^a and TS^b . These relays SS^a and SS^b are of the three position polarized type having their contacts operated to right or left hand positions in accordance with the normal or reverse positions of their respective track switches. These relays are energized over individual polarized circuits controlled by the usual point detector or switch box contacts for the respective switches so as to apply one polarity or the other to the corresponding relay in accordance with the extreme locked position of the track switch. When a track switch is in an intermediate unlocked position or is in operation, the corresponding SS relay is deenergized and the contacts of that relay assume neutral positions. 70 With each of the signals S^3, S^5, S^7 , and S^9 , are associated home relays HR^3, HR^5, HR^7 , and HR^9 respectively which, when energized, cause the least restrictive indications of the associated signal to be displayed, such for example as yellow in the case of the dwarf signals. When these HR

relays are deenergized, the most restrictive indication of the respective signal is displayed, such for example as red. The indications of the various signals S have been conveniently indicated by showing or repeating the lights at the HR relays rather than carry the wires to the respective signals. It will be noted, however, that the relay HR^9 is shown as directly controlling the signal S^9 to illustrate specifically what is intended. Also, the relay HR^7 , when energized, permits either the green or the yellow indication to be selected in accordance with the energization or deenergization of a distant relay DR^7 which is controlled by the home relay of the next succeeding signal location in accordance with the condition of the automatic block signals located outside the interlocking plant in the usual manner well known to those skilled in the art.

The approach locking group of relays includes, thermal time element relays TH^3, TH^5 , and TH^9 associated with their respective signals as their distinctive exponents indicate, and thermal stick relays THS^3, THS^5 , and THS^9 , that is, relays which have stick circuits governed by their respective thermal relays. A similar arrangement of a thermal time element relay, used in conjunction with a stick relay to produce a time element approach locking means, is shown and described in an application by S. N. Wight Ser. No. 389,446 filed August 30, 1929, now U. S. Letters Patent 2,038,504. Thus the various ways, in which such a combination may be used will not be explained except as pertains to the present invention.

The group of directional stick route relays for the east bound route includes, relays ES^2, ES^4 , and ES^6 , while the west bound group includes relays WS^2, WS^4 , and WS^6 . A track repeater stick relay TRS^6 is used in conjunction with the track repeater relay TR^6 to maintain a stop indication at signal S^7 after a train has passed said signal until it is again manually cleared by the operator. This signal S^7 also has an approach locking stick relay AS^7 to provide that once the signal S^7 has been cleared and a train has accepted the route, said route can not be altered except after the release of the time element contacts TEC . A stick relay PBS^4 is associated with the push button PB to maintain the condition established by said push button until certain conditions have been restored to normal.

The switch machines are controlled from their respective levers in the usual manner which has been shown more specifically for the switch machine SM^b . This control, of course, can be repeated for the switch machine SM^a but for convenience is only indicated. The promiscuous or unauthorized control of the switch machines SM^a and SM^b is prevented by lock relays LR^a and LR^b respectively which relays are of the slow acting type and are energized by the movement of a proper switch machine lever SML to a new governing position providing the associated track section and route established are in proper conditions, as indicated by the respective directional stick route relays and the track repeater relay of the track section in which the track switch is located.

It is believed that the usefulness and the various interrelated functions and operations of such a system will be more readily understood by further describing the system from the standpoint of operation.

Operation of the system

The system is shown in a normal condition with

the track switches TS^a and TS^b in normal positions permitting the passage of traffic over the main track in accordance with the governing signals. This information concerning the track switches is repeated or indicated in the interlocking tower by the respective SS relays with each of said relays having its polar contacts energized to right hand extreme positions. Also, as all the track sections are unoccupied, the track repeater relays TR will indicate this condition in the interlocking tower by assuming energized positions. The various signal control levers SL are in their normal "at stop" positions, thus deenergizing the relays R which in turn deenergize the relays HR. With the HR relays deenergized, the most restrictive indication of each signal will be displayed, which fact may be indicated in the interlocking tower by suitable indicating lamps on the miniature track diagram (not shown). Also, the switch machine levers SML are shown in their normal positions in correspondence with the normal positions assumed by their respective track switches TS. With the track repeater relays TR and the home relays HR in their normal positions, the thermal stick relays THS will assume energized positions which in turn cause the various directional stick route relays ES and WS to be energized through their respective circuits. These various conditions and circuits are maintained with the system in the normal condition, as above stated, by circuits and devices operating as more specifically pointed out below.

The control wires of the relays have been indicated as supplied with suitable electrical energy from suitable sources which, for convenience, have only been indicated as the positive and negative terminals of suitable sources by reference characters B+ and B- respectively. It is to be understood that these sources may be either alternating current or direct current in any suitable way to meet the requirements of practice without in any manner affecting the present invention.

The relay THS³ is energized through a circuit traced as follows:—from the positive terminal of a suitable source of electrical potential indicated as B+, through back contact 10 of relay HR³, wires 11 and 12, front contact 13 of track repeater relay TR³, wires 14, 15, and 16, winding 50 of relay THS³, to the negative terminal of the suitable source indicated as B-. The contacts of the relay THS³ are thus maintained in energized positions which completes an energizing circuit for the relay ES² that is traced as follows:—from the positive terminal of a suitable source of electrical potential indicated as B+, through front contact 8 of relay THS³, wires 17 and 18, front contact 19 of relay TR², wires 20 and 21, winding of relay ES², to the negative terminal of the suitable source indicated as B-. With the contacts of relay ES² in an energized position, the energizing circuit for the relay ES⁴ is completed, which is traced as follows:—from the positive terminal of a suitable source of electrical potential indicated as B+, through front contact 22 of relay ES², wires 23, 24, and 25, front contact 26 of track repeater relay TR⁴, wires 27 and 28, winding of relay ES⁴, to the negative terminal of the suitable source indicated as B-.

The approach locking stick relay AS⁷ is energized through a pick-up circuit traced as follows:—from the positive terminal of a suitable source of electrical potential indicated as B+, through back contact 31 of relay HR⁷, wires 32 and 33, front contact 34 of relay ES⁴, wires 35,

36, 37, and 38, winding of relay AS⁷ to the negative terminal of the suitable source indicated as B-. The raising of the contacts of relay AS⁷ completes the energizing holding circuit of the relay ES⁶ which is traced as follows:—from the positive terminal of a suitable source of electrical potential indicated as B+, through front contact 40 of relay AS⁷, wires 41 and 42, front contact 43 of relay TR⁶, wires 44 and 45, winding of relay ES⁶, to the negative terminal of the suitable source indicated as B-. 10

The relay THS⁹ is energized through a circuit traced as follows:—from the positive terminal of a suitable source of electrical potential indicated as B+, through back contact 50 of relay HR⁹, wires 51 and 52, front contact 53 of relay TR⁸, wires 54, 55, and 56, winding of relay THS⁹, to the negative terminal of the suitable source indicated as B-. With the contacts of relay THS⁹ in energized positions, the energizing circuit for relay WS⁶ is traced as follows:—from the positive terminal of a suitable source of electrical potential indicated as B+, through front contact 57 of relay THS⁹, through wires 58 and 59, front contact 60 of relay TR⁶, wires 61 and 62, winding of relay WS⁶, to the negative terminal of the suitable source indicated as B-. With the contacts of relay WS⁶ in energized positions, the energizing circuit for WS⁴ is traced as follows:—from the positive terminal of a suitable source of electrical potential indicated as B+, through front contact 65 of relay WS⁶, wires 66, 67, and 68, front contact 69 of relay TR⁴, wires 70 and 71, winding of relay WS⁴, to the negative terminal of the suitable source indicated as B-. 30

The relay THS⁵ is energized through a circuit which is traced as follows:—from the positive terminal of a suitable source of electrical potential indicated as B+, through back contact 73 of relay HR⁵, wire 74, front contact 75 of relay WS⁴, wires 76, 77, and 78, winding of relay THS⁵, to the negative terminal of a suitable source indicated as B-. With the contacts of relay THS⁵ in an energized position, the energizing circuit for the relay WS² is traced as follows:—from the positive terminal of a suitable source of electrical potential indicated as B+, through front contact 80 of relay THS⁵, wires 81 and 82, front contact 83 of relay TR², wires 84 and 85, winding of relay WS², to the negative terminal of the suitable source indicated as B-. 45

The track repeater stick relay TRS⁶ is energized through a circuit which is traced as follows:—from the positive terminal of a suitable source of electrical potential indicated as B+, through front contact 89 of relay TR⁶, wires 90 and 91, back contact 92 of relay R⁷, wires 93 and 94, winding of relay TRS⁶, to the negative terminal of the suitable source indicated as B-. 50

The above description points out those pick-up circuits upon which the system is dependent for establishing the normal conditions of the various devices included in the system. The various circuits that are closed during the operating conditions dependent upon the movement of control levers and the passage of trains will be pointed out and described more specifically in considering typical operations of the system. 60

However, there are various auxiliary circuits which are closed while the system is in its normal condition, which auxiliary circuits have their usefulness more particularly during the operation of the system and will therefore be more readily understood by reference to the description pointing out certain typical operations. 70

For example, the relays THS³, THS⁵, and THS⁹ have auxiliary stick circuits including front contacts 95, 96, and 99 respectively. These stick circuits include the thermal elements of their corresponding thermal relays TH³, TH⁵, and TH⁹ respectively, but the current which flows in these auxiliary stick circuits is insufficient to actuate the thermal element relays. The function of these stick circuits is more particularly pointed out hereinafter in connection with the clearing of signal S⁹ for allowing the passage of a train in a west bound direction.

Further, the relay AS⁷, which functions similar to the relays THS but is associated with a mechanical time element relay TEC, has a stick circuit closed from B+, through back contact 31 of relay HR⁷, wires 32, 184, 185, and 186, front contact 187 of relay AS⁷, wires 188 and 38, windings of relay AS⁷, to B-. This stick circuit serves a similar purpose as the stick circuits of the thermal time element stick relays THS.

Also, the relays WS², WS⁴, WS⁶, ES², ES⁴, and ES⁶ are provided with stick circuits including front contacts 190, 191, 192, 193, 194, and 161 respectively. These stick circuits for the respective relays serve to shunt the front contact of their corresponding track repeating relay for purposes more specifically explained hereinafter.

The track repeating stick relay TRS⁶ is provided with a stick circuit closed from B+, through front contact 89 of relay TR⁶, wires 90 and 195, front contact 196 of relay TRS⁶, wires 197 and 94, windings of relay TRS⁶, to B-. This stick circuit serves to shunt out the back contact 92 of relay R⁷ for the purpose of causing the signal S⁷ to be a stick signal, as hereinafter pointed out.

Let us assume that the operator, in anticipating the entrance of a train in a west bound direction into his interlocking territory, desires to set up a route onto the turn-out track TO^b. As the signals, governing traffic over the track section T^b including track switch TS^b, are at stop, the first act necessary for the operator will be to operate the switch machine lever SML^b to a dotted line reverse position. This will immediately operate the switch machine SM^b as the approach locking time element of the thermal relay TH⁹ is ineffective due to the fact that there is no train upon the track section T^b approaching the signal S⁹ to accept its indication; and also due to the fact that the signal S⁹ is giving a stop indication. In other words, should a train enter the track section T^b to receive an indication from the signal S⁹, the track repeater relay TR⁸ would be deenergized opening its front contact 53 which is included in the circuit of the relay THS⁹ as heretofore traced. However, a multiple path or a stick circuit including the winding of the thermal relay TH⁹, wire 98, front contact 99 of relay THS⁹, and wire 100, provides that the relay THS⁹ shall remain in an energized position although a train is approaching, so long as the signal S⁹ continues to give a stop indication.

Let us assume that a train is approaching the interlocking plant in a west bound direction and treads upon the track section T^b, which fact is indicated to the operator who then proceeds to set up the route onto the turn-out track TO^b as heretofore mentioned. He operates the switch machine lever SML^b to a reverse dotted line position which operates its contacts 102 and 103 to reverse dotted line positions. As the contact 102 passes its central intermediate position, contact is made for a sufficient length of time to com-

pletely energize the lock relay LR^b through a circuit which is traced as follows:—from the positive terminal of a suitable source of electrical potential indicated as B+, through front contact 105 of relay WS⁶, wire 106, front contact 107 of relay TRS⁶, wire 108, front contact 109 of relay ES⁶, wire 110, central contact 102, wire 111, winding of relay LR^b, to the negative terminal of the suitable source indicated as B-. The relay LR^b is of the slow releasing type remaining a sufficient period of time in an energized condition to complete the reverse operating circuit for switch machine SM^b after the contact 103, controlled by switch machine lever SML^b, reaches its dotted line reverse position. This reverse energizing circuit for the switch machine SM^b is traced as follows:—from the negative terminal of a suitable source of electrical potential indicated as B-, through reverse contact 103 of lever SML^b, wire 113, front contact 114 of relay LR^b, wires 115 and 116, through the operating mechanism of the switch machine SM, wire 117, front contact 118 of relay LR^b to the mid-point, or half voltage tap of the suitable source, known as the common terminal and designated as C. This circuit is completed for a sufficient period of time to effect the complete control of the switch machine SM^b. The switch machine SM^b now controls the track switch TS^b to a reverse position. When the lock relay LR^b becomes deenergized, the control line wires 116 and 117 for the switch machine SM^b are shunted through back contacts 114 and 118, and through wires 119 and 120 respectively, which prevents any foreign currents from falsely operating the switch machine.

The train is now approaching the signal S⁹, and as the track switch TS^b is in a reverse locked position, as indicated by relay SS^b, the operator may clear the signal S⁹ by moving the signal lever SL⁹ to the dotted line position.

With the signal lever SL⁹ in the dotted line position, the relay R⁹ is energized through closed contact 121 as is obvious from the drawings. The energizing circuit for relay HR⁹ is now traced as follows:—from the positive terminal of a suitable source of electrical potential indicated as B+, through the various signal control circuits (not shown) associated with the turn-out track TO^b similar to those shown for the main track, through contact 122 of relay SS^b in a reverse dotted line position, wire 123, front contact 124 of relay R⁹, wire 125, winding of relay HR⁹, wire 126, front contact 127 of relay R⁹, to the negative terminal of the suitable source indicated as B-. The relay HR⁹ is now energized, which completes the energizing circuit for the yellow indication of signal S⁹ from the positive terminal of a suitable source of electrical potential indicated as B+, through front contact 128 of relay HR⁹, wire 129, yellow indicator lamp of signal S⁹ to the negative terminal of the suitable source indicated as B-.

Also, the stick circuit for the relay THS⁹ is opened at back contact 50 of relay HR⁹. The dropping of contact 57 of relay THS⁹ opens the energizing circuit of the relay WS⁶ as heretofore traced, thus opening front contact 105 of relay WS⁶, which prevents the energization of lock relay LR^b in the event that the operator should promiscuously or unintentionally attempt to operate the switch machine lever SML^b to the normal position. The opening of front contact 65 of relay WS⁶ opens the energizing circuit of the relay WS⁴ as heretofore traced, but as the track switch TS^b is in a reverse position which

condition is indicated by the relay SS^b for reasons previously explained, the relay WS⁴ now has an energizing circuit traced as follows:—from the positive terminal of a suitable source of electrical potential indicated as B+, contact 130 of relay SS^b in a reverse position, wires 131, 67, and 68, front contact 69 of relay TR⁴, wires 70 and 71, winding of relay WS⁴, to the negative terminal of the suitable source indicated as B—.

10 As the train passes over the track section T⁶ onto the turn-out track T^{0b}, the track repeater relay TR⁶ is deenergized which opens the energizing circuit for relay TRS⁶ at the front contact 89 of relay TR⁶. The deenergization of relay 15 TRS⁶ opens its front contact 107 which further insures deenergization of the lock relay LR^b. Thus, the switch machine SM^b is effectually prevented from unauthorized operation.

Let us now consider that the train has passed 20 off from the track sections T⁸ and T⁶, so that the track repeater relays TR⁸ and TR⁶ have again been energized. With the track repeater TR⁶ energized, front contact 89 again closes the energizing circuit for relay TRS⁶, as heretofore traced, 25 which, when energized, closes front contact 107. The operator having been given an indication of the passage of the train over track section T⁶, returns the signal control lever SL⁹ to a normal position which deenergizes relay HR⁹, thus closing the energizing circuit for relay THS⁹ through 30 back contact 50 of relay HR⁹ and front contact 53 of track relay TR⁸. The energization of relay THS⁹ closes front contact 57 which again energizes relay WS⁶ through the same circuit as heretofore traced which closes its front contact 35 105. The energizing circuit of relay LR^b may now be completed by movement of the control lever SML^b to a normal position which operates the switch machine SM^b and track switch TS^b to 40 normal positions. The normal locked position of the switch TS^b is indicated by the relay SS^b which breaks the energizing circuit of the relay WS⁴ through the reverse contact 130, but a circuit for relay WS⁴ is closed through front contact 65 45 of relay WS⁶ which is now energized. Thus, it is obvious from the above description, that the normal operation of the interlocking system in setting up a route for a train and safe-guarding its 50 passage over the route by preventing unauthorized changing of that route is accomplished in a safe and efficient manner. Also, as soon as the train leaves the particular section, that section may be immediately used for another route without the loss of any time.

55 If the operator, noting the approach of a train on track section T⁸, had reversed the track switch TS^b and cleared the signal S⁹, as above explained, and then changed his mind for one reason or another causing the signal S⁹ to give a 60 stop indication, he could not return the track switch TS^b to a normal position except after a predetermined time as governed by the pick-up time period of the thermal relay TH⁹. This is true because the relay HR⁹ having been energized would have opened the stick circuit of relay THS⁹ at the opened back contact 58 of relay HR⁹ deenergizing the relay THS⁹ and thus opening its stick energizing circuit at front contact 65 99 of relay THS⁹. The circuit for energizing the relay LR^b is opened as heretofore explained. The train, being upon track section T⁸, causes the front contact 53 of relay TR⁸ to be in a retracted position. Thus, when the signal S⁹ is returned to the stop indication in the face of the oncoming 70 train, energy is placed upon the winding of the 75

thermal relay TH⁹ through a circuit traced as follows:—from the positive terminal of a suitable source of electrical potential indicated as B+, through back contact 50 of relay HR⁹, wire 51, thermal winding of relay TH⁹, wire 98, back contact 99 of relay THS⁹, to the negative terminal of the suitable source indicated as B—. As the winding of the relay TH⁹ is now across the terminals of a suitable source of potential, the current flow is sufficient to heat its thermal 10 elements causing its contacts 182 and 183 to close after a predetermined period of time which closes a pick-up circuit for the relay THS⁹. This pick-up circuit includes contacts 182 and 183 which bridge the open contacts 53 and 99 as is 15 obvious from the drawings. The energization of relay THS⁹ effects the partial completion of the energizing circuit for relay LR^b which may be completed by the movement of lever SML^b operating contact 102. However, this cannot be accomplished except after the predetermined time mentioned which is sufficient for the train on track section T⁸, if at the entrance to the section, to come to a stop in the face of signal S⁹; or, should the train pass the signal S⁹, having 20 received its indication too tardily, the time element would be sufficient for the train to deenergize the track repeater relay TR⁸ which then deenergizes relay TRS⁶ and thus opens the energizing circuit of lock relay LR^b at front contact 107 of relay TRS⁶ in time to prevent the control of the switch TS^b beneath the moving train. 25

Let us again consider that the system is in a normal condition as originally set forth, and that 30 the operator is switching a train through various routes of the interlocking plant which at this time enters the track section T⁰. In view of this, the operator clears the signal S³ to allow this train to proceed in an east bound direction. However, 35 shortly thereafter a high speed passenger train for example, enters on the track section T⁸, that the operator desires to allow to enter the interlocking plant with as little time delay as possible, and thus immediately operates the signal 40 lever SL⁹ to a dotted line position to clear the signal S⁹ without thinking of the first train which has accepted the signal S³. Such an exigency produces no particularly unsafe condition as the signal SL⁹ is prevented from assuming a clear 45 50 condition, thus stopping the passenger train before any harmful result is accomplished. The manner in which the stated result is accomplished will now be explained.

With the switch TS^a in a normal position, the 55 lever SL⁹ will be in a dotted line position to clear the signal S³. The relay R³ is energized through contact 135 as is obvious from the drawings. The relay HR³ is energized through a circuit traced as follows:—from the positive terminal of a suitable source of electrical potential indicated as B+, through front contact 136 of relay WS⁴, wires 137 and 138, back contact 139 of relay R³, wire 140, contact 141 of relay SS^a in a right-hand normal position, wire 142, front contact 143 of relay 60 R³, wires 144 and 145, winding of relay HR³, wire 146, front contact 148 of relay R³, to the negative terminal of the suitable source indicated as B—. The yellow indication of the signal S³ is given with contact 150 of relay HR³ in an energized position. Also, the energizing circuit for the relay THS³ is broken at back contact 10 of relay HR³. This in turn opens the energizing circuit of relay ES² at the front contact 8 of relay THS³, which condition in turn opens the en- 70 75

ergizing circuit of relay ES^4 at the front contact 22 of relay ES^2 .

As heretofore assumed, the operator moves the lever SL^9 to a dotted line position intending to clear the signal S^9 . The relay R^9 is energized but fails to energize the relay HR^9 to clear the signal S^9 because of the deenergization of the relay ES^4 in accordance with the route set up for the train proceeding in an east bound direction. 10 It is pointed out that, if the train proceeding in the east bound direction were not present and the east bound route were normal, the relay HR^9 would be energized through a circuit traced as follows:—from the positive terminal of a suitable 15 source of electrical potential indicated as B^+ , through front contact 151 of relay ES^4 , wires 152 and 153, back contact 154 of relay R^7 , wires 155 and 156, time element contact 157 in a normal position, wire 158, contact 122 of relay SS^b in 20 a right-hand normal position, wire 123, front contact 124 of relay R^9 , wire 125, winding of relay HR^9 , wire 126, front contact 127 of relay R^9 , to the negative terminal of the suitable source indicated as B^- . Inasmuch as the relay ES^4 is 25 deenergized due to the clearing of signal S^3 , the energizing circuit for the relay HR^9 is opened at front contact 151 of relay ES^4 . The passenger train proceeding in a west bound direction is thus caused to stop at the signal S^9 preventing any 30 unsafe condition.

Again considering that the interlocking system is in the normal condition as shown, let us assume that a train is proceeding in a west bound direction entering the interlocking plant on the track section T^8 . Further let us assume that this interlocking plant, for example, is the end of the divisional run and the train at this point must change engines. The operator clears the signal S^9 and allows the train to proceed over the track section T^6 onto the track section T^4 at which point the train stops in accordance with the stop indication given by the signal S^5 . The operator then clears the signal S^5 which allows the uncoupled engine to proceed in a westward direction 40 to some other part of the interlocking plant. In due time, an engine backs onto the track section T^6 , in readiness to be coupled to the train standing on track section T^4 . Under normal conditions the operator could not clear the signal S^3 due to 45 the train which is standing on the track section T^4 . In other words the train from the east deenergizes the relay WS^4 , thus opening the energizing circuit for the relay HR^3 at front contact 136 of relay WS^4 . However, the present invention provides special means for such occasions. The signal S^3 is capable of being cleared if the 50 push button PB is depressed, as this energizes the relay PBS^4 which relay is maintained energized through stick circuits as long as either the relay WS^4 or ES^4 is deenergized. The energization of the relay PBS^4 places positive potential 55 upon the energizing circuit for the relay HR^3 .

More specifically, the lever SL^9 is placed in a dotted line position closing contact 121 and energizing relay R^9 as heretofore described. The relay HR^9 is now energized through front contacts 127 and 124 of relay R^9 , normal contact 122 of relay SS^b , normal contact 157 of time element contactor TEC , back contact 154 of relay R^7 , and front contact 151 of relay ES^4 . The energization of relay HR^9 deenergizes the relay THS^9 at back contact 50, which in turn deenergizes the relay WS^6 at front contact 51 of relay THS^9 , which in turn deenergizes the relay WS^4 70 at front contact 65 of relay WS^6 . The train now 75

passes in a westward direction in accordance with the signal S^9 and treads upon the track section T^6 and T^4 coming to stop in approach to signal S^5 . It will be noted that, although the track repeater relays TR^6 and TR^4 are deenergized, the 5 east bound directional relays ES^4 and ES^6 are not deenergized as they are maintained energized through stick circuits, for example, ES^6 is energized with the track repeater TR^6 deenergized opening the circuit as heretofore traced at front contact 43, which is shunted as is obvious from the drawings, by the stick circuit including wire 160, front contact 161 of relay ES^6 and wire 162. The other directional route relays are similarly held in energized positions through their stick 15 circuits when a train passes in a direction opposite to the one under which they are supposed to be deenergized. In other words, their pick-up circuit includes a contact of a track repeater relay which may be deenergized without deenergizing the associated directional route relay once said relay has been energized to close its stick circuit. It is of course understood that the directional route relays are deenergized as heretofore mentioned. 20 25

As the train comes to a stop on the track section T^4 , the operator may clear the signal S^5 by moving a lever SL^5 to a dotted line position closing contact 165 which energizes the relay R^5 as is obvious from the drawings. The relay HR^5 is 30 now energized through a circuit traced as follows:—from the positive terminal of a suitable source of electrical potential indicated as B^+ , through back contact 143 of relay R^3 , wire 142, contact 141 of relay SS^a in a right hand normal 35 position, wire 140, front contact 139 of relay R^5 , wires 166 and 167, winding of relay HR^5 , wire 168, front contact 169 of relay R^5 , to the negative terminal of the suitable source indicated as B^- . The signal S^5 is now caused to display a 40 yellow indication with its contact 170 in an energized position which is obvious from the drawings.

After the engine is uncoupled from the train, it may proceed in a west bound direction in 45 accordance with the signal S^5 and with any other signals which it may encounter on its way through the interlocking plant.

We will now assume that the reserve engine is proceeding in an east bound direction to be 50 coupled to the standing train and approaches the signal S^3 which cannot at this time be cleared although the signal S^5 is returned to a stop position by moving the lever SL^5 to its present normal position, as the energizing circuit for the 55 relay HR^3 is opened at front contact 136 of relay WS^4 .

The operator now depresses the self-restoring push button PB which energizes the relay PBS^4 60 through a circuit which is traced as follows:—from the positive terminal of a suitable source of electrical potential indicated as B^+ , through back contact 136 of relay WS^4 , wires 171 and 172, winding of relay PBS^4 , wires 173 and 174, push button PB in a depressed position, to the negative terminal of the suitable source indicated as B^- . The relay PBS^4 is held in an energized position, although the push button PB is automatically restored to a non-contacting position, 70 through a stick circuit traced as follows:—from the positive terminal of a suitable source of electrical potential indicated as B^+ , through back contact 136 of relay WS^4 , wires 171 and 172, winding of relay PBS^4 , wires 173 and 175, front 75

contact 176 of relay PBS⁴, to the negative terminal of the suitable source indicated as B-.

The relay HR³ may now be energized through a circuit traced as follows:—from the positive terminal of a suitable source of electrical potential indicated as B+, through front contact 180 of relay PBS⁴, wires 181 and 138, back contact 139 of relay R⁵, wire 140, contact 141 of relay SS^a in a right-hand normal position, wire 142, front contact 143 of relay R³, wires 144 and 145, winding of relay HR³, wire 146, front contact 148 of relay R³, to the negative terminal of the suitable source indicated as B-.

The signal S³ now gives a clear proceed indication with the contact 150 of relay HR³ in a raised position. With the relay HR³ energized, the relay THS³ is deenergized at back contact 10 of relay HR³, which in turn deenergizes the relay ES² at front contact 8 of relay THS³, which in turn deenergizes the relay ES² at front contact 22 of relay ES². The reserve engine accepts the signal S³ and is coupled with the train standing on track section T⁴. The operator may now return the lever SL³ to a normal non-clear position causing the signal S³ to give a stop indication. Also, the signal lever SL⁵ is moved to a clear position energizing relay R⁵ which in turn causes the relay HR³ to be energized through its circuit, as heretofore traced, including front contacts 139 and 169 of the relay R⁵, contact 141 of relay SS^a in a right-hand normal position and back contact 143 of relay R³. When the train has proceeded over the track section T², onto the track section T⁰ and thence onto the various other track sections included in its route in a west bound direction out of the interlocking plant, the signals S³, S⁵, S⁷, and S⁹ may be returned to their normal stop conditions which restores the relays of the interlocking plant to their normal positions opening the stick circuit of relay PBS⁴ at back contact 138 of WS⁴ and back contact 151 of relay ES⁴ so that the system assumes a full normal condition.

When a train proceeds in an east bound direction through the interlocking plant, the signal S⁷ is caused to give a clear indication, it is assumed, in accordance with the conditions of traffic ahead in the automatic block signal territory outside the interlocking plant, as indicated in the interlocking plant by a directional relay DR⁷. This relay DR⁷ is controlled through the contacts of the home relay at the next signal located outside the interlocking plant. The track relay TRS⁶ causes this signal S⁷ to be a stick signal, that is, to continue to give a stop indication after the train has passed beyond its track section T⁶ until the operator again causes it to give a clear indication. Also, the time element contractor TEC is employed to give an approach locking time period similar to that furnished by the thermal relays TH but of longer duration to take care of the higher speed trains which the high speed three indication signal governs. However, as it is no part of the present invention to employ stick signals, which are well known to those skilled in the art, or manual release time contractors as are often used, the operation and description of such a combination will not be described in detail. Such a combination is merely shown in connection with the present invention to show the adaptability of the present invention to the various conditions met in an interlocking plant of the usual type.

It is to be understood from the foregoing that semi-automatic signals could be used at the several locations shown without in any manner af-

fecting the present invention. Also, the present disclosure shows only the circuits and devices associated with a stretch of main track; and it is to be understood that similar circuits may be associated with the turn-out track sections without in any manner affecting the operation of the system or departing from the present invention. It may be further stated that the control of the signals may be of the remote type or the direct control type whichever most advantageously fits the circumstances to be met.

It is obvious from the above description that an interlocking system has been provided with approach locking and with sectional release route locking which is accomplished by establishing directional routes by the combination of relays and devices which are used, with only those devices which are governed by the particular direction of the route set up being affected at one time. Also, the interlocking system, as shown, gives head-on directional protection, that is, two routes opposing each other in direction may not possibly be set up. Although no rear-end protection has been shown except in the case of one signal, it is to be understood that the various other signals could be provided to give the same protection.

Having described various devices and circuits constructed and arranged as one embodiment of the present invention, it is to be understood that the embodiment shown is not to be used in any way to limit the number of uses or combinations in which the present invention may be incorporated, as the embodiment shown is used only to facilitate in the disclosure of the present invention; also, various modifications, adaptations and alterations may be made to the interlocking system shown as the embodiment of the present invention to meet the various requirements of practice without departing from the spirit or scope of the invention as set forth in the appended claims.

Having described my invention, I now claim:

1. In an interlocking system for railroads, a plurality of switches having power operated switch machines, a plurality of signals one for governing traffic in each direction over each switch, means preventing the clearing of those of said signals governing traffic in one direction when those of said signals governing traffic in the opposite direction over the same route are cleared, said means being effective until the passage of a train if said train has accepted said route, means for locking those of said switches in said route from movement after said route has been set up, means releasing each of said switches sequentially from said route as soon as a train passes beyond each of said switches, and means permitting control of those of said signals governing traffic in the same direction as said route independently of train movements.

2. In an interlocking plant for railroads, a route set up through said plant including a series of switches, a signal governing traffic in one direction located in approach to each of said switches and a signal governing traffic in an opposite direction located in approach to each of said switches with said route established in one direction only by the clearing of said signal governing that direction, directional approach locking means effective for each switch with said route set up, interlocking means preventing said opposing signals from clearing, and means for releasing said opposing signal interlocking means for allowing a train to proceed toward another train under signals with the second train standing on a particular track section.

3. In an interlocking system for railroads, a track section, one signal governing traffic in approach to said track section in one direction, one control lever governing said signal, another signal governing traffic in approach to said track section in an opposite direction, another control lever governing said another signal, a series of directional stick route relays successively de-energized when said another control lever is in a clearing position, and means preventing the clearing of said one signal with said one control lever in a clearing position when said another control lever is in a clearing position, said means including said directional stick route relays. 5
- 10 4. In an interlocking system for railroads, a track section, one signal governing traffic in one direction over said track section, one control lever governing the clearing of said one signal, another signal governing traffic in an opposite direction over said track section, another control lever governing the clearing of said another signal, a distant signal in respect to said another signal, a home relay for clearing said one signal when energized, a series of directional stick route relays 15 successively de-energized when said distant signal is cleared, and means for energizing said home relay, said means including said one control lever, said another control lever, and said directional stick route relays. 20
- 25 5. In an interlocking system for railroads, one track section having a track switch, another track section having a track switch, signal means governing traffic in both directions over said one track section, signal means governing traffic in both directions over said other track section, one directional stick route relay associated with said one track section being de-energized with said signal means for said one track section cleared for traffic in one direction, another directional stick route relay associated with said other track section being de-energized when said one directional stick route relay is de-energized except when said track switch in said one track section is reversed, and means preventing the clearing of 30 said signal means for said other track section in a direction in opposition to the direction established in said one track section except when said track switch in said one track section is reversed, said means including said other directional stick route relays. 35
- 40 6. In an interlocking system for railroads, one track section having a track switch, another track section having a track switch, an intermediate track section separating said one track section from said other track section, signal means governing traffic in both directions over said one track section, signal means governing traffic in both directions over said other track section, one directional stick route relay associated with said one track section being de-energized with said signal means for said one track section cleared for traffic in a direction in approach to said other track section, one directional stick route relay associated with said intermediate track section being de-energized with said one directional stick route relay associated with said one track section de-energized, one directional stick route relay associated with said other track section being de-energized with said signal means for said other track section cleared for traffic in a direction in approach to said one track section, another directional stick route relay associated with said intermediate track section being de-energized with said one directional stick route relay 45 associated with said other track section de-energized, interlocking means preventing the clearing of said signal means associated with said one track section or said other track section with either establishing a direction of traffic in opposition to the other, said means including said one and said other directional stick route relays associated with said intermediate track section, and means for manually releasing said interlocking means when said intermediate track section is occupied. 50
- 10 7. In an interlocking system for railroads, a track section having a track switch, control means for operating said track switch, one signal governing traffic in one direction over said track section, another signal governing traffic in an opposite direction over said track section, one home relay for clearing, when energized, said one signal, another home relay for clearing, when energized, said other signal, one directional stick route relay de-energized when said one home relay is energized, another directional stick route relay de-energized when said other home relay is energized, a lock relay preventing said control means from operating said track switch except when said lock relay is energized, and means 55 de-energizing said lock relay including said one and said other directional stick route relays. 20
- 25 8. In an interlocking system for railroads, a track section comprising a plurality of track circuits, one signal governing traffic in approach to said track section in one direction, one control lever governing said signal, another signal governing traffic in approach to said track section in an opposite direction, another control lever governing said another signal, route locking means including a series of directional stick route relays one for each of said track circuits said stick route relays being deenergized when said another signal is cleared, means preventing the clearing of said one signal when said another signal is cleared said means including said stick route relays, and means maintaining said stick route relays deenergized independently of said another signal upon the entrance of a train onto said track section said stick route relays 40 being successively energized upon the passing of the train over the respective track circuits if said another signal is at stop. 45
- 30 9. In an interlocking system for railroads, a plurality of track sections, a track circuit associated with each of said track sections each of said track circuits having a track relay, a signal governing traffic in one direction into a route over said plurality of track sections, a directional stick relay associated with each of said track sections, 50 a pick-up circuit for each of said directional stick relays said pick-up circuit including a front contact of the corresponding track relay and a front contact of each preceding directional stick relay, a stick circuit for each directional stick relay said 55 circuit including a front contact of the corresponding directional stick relay for shunting said front contact of the corresponding track relay, and means for opening the stick and pick-up circuits of the first section in advance of said signal when said signal indicates clear, whereby each of said directional stick relays is deenergized by the clearing of said signal, and whereby said relays may be successively picked up upon the passage of a train over said track sections if 60 said signal is at stop. 65
- 40 10. In an interlocking system for railroads, a track section having a track relay, a signal governing traffic over said track section in one direction, a home relay for controlling said signal, a 70
- 75

- directional stick relay associated with said track section, a pick-up circuit for said directional stick relay including a contact controlled by said home relay and a front contact of said track relay, a stick circuit for said directional stick relay including said contact controlled by said home relay and a front contact of said directional stick relay, and traffic controlling means governed by said directional stick relay.
- 5 11. In an interlocking system for railroads, a series of track sections, a track relay associated with each track section of said series, a directional stick relay associated with each track section of said series, a signal governing traffic over 10 said series of track sections, a pick-up circuit for each of said directional stick relays including a front contact of its corresponding track relay and a front contact of its next preceding directional stick relay in an order extending in the 15 direction of traffic governed by said signal except the first of said directional stick relays, a pick-up circuit for the first of said directional stick relays including a front contact of its corresponding track relay and a contact closed only when said 20 signal indicates stop, a stick contact on each of said directional stick relays for shunting said front contact on said corresponding track relays, and traffic controlling means governed by each 25 of said directional stick relays.
- 30 12. In an interlocking system for railroads, a series of track sections, a track relay associated with each track section of said series, a directional stick relay associated with each track section of said series, a signal governing traffic 35 over said series of track sections, a pick-up circuit for each of said directional stick relays including a front contact of its corresponding track relay and a front contact of its next preceding directional stick relay in an order extending in 40 the direction of traffic governed by said signal except the first of said directional stick relays including a front contact of its corresponding track relays and a contact closed only when said signal indicates stop, a stick contact on each of said 45 directional stick relays for shunting said front contact on said corresponding track relays, and means governed by said directional stick relays for preventing traffic movement in a direction opposite to the direction governed by said signal 50 when said signal is cleared.
13. In an interlocking system for railroads, a track section having a track switch, a detector track circuit having a track relay said detector track circuit being associated with said track section, a signal for governing traffic over said track section, means for operating said track switch, an approach track section, an approach track circuit having an approach track relay said approach track circuit being associated with said approach 55 track section, a time element stick relay, a pick-up circuit for said time element stick relay including a front contact of said approach track relay and a contact closed only when said signal displays stop, a stick circuit for said time element stick relay including a front contact of said time element stick relay and a contact closed only when said signal displays stop, means for closing an auxiliary pick-up circuit after the elapse of a predetermined time if said signal is put to stop 60 when said approach track relay is deenergized, a directional stick relay associated with said detector track circuit, a pick-up circuit for said directional stick relay including a front contact of said detector track relay and a front contact of 65 said time element stick relay, a stick circuit for said time element stick relay including a front contact on said time element stick relay and said front contact on said time element stick relay, and means preventing operation of said track switch by said operating means when said directional stick relay is deenergized.
14. In an interlocking system for railroads, a track section having a track switch, a detector track circuit having a track relay said detector track circuit being associated with said track section, a signal for governing traffic over said track section, means for operating said track switch, an approach track section, an approach track circuit having an approach track relay said approach track circuit being associated with said approach 10 track section, a time element stick relay, a pick-up circuit for said time element stick relay including a front contact of said approach track relay and a contact closed only when said signal displays stop, a stick circuit for said time element 15 stick relay including a front contact of said time element stick relay and a contact closed only when said signal displays stop, means for closing an auxiliary pick-up circuit after the elapse of a predetermined time if said signal is put to stop 20 when said approach track relay is deenergized, a directional stick relay associated with said detector track circuit, a pick-up circuit for said directional stick relay including a front contact of said detector track relay and a front contact 25 of said time element stick relay, a stick circuit for said directional stick relay including a front contact of said time element stick relay and a front contact of said time element stick relay, and means preventing operation of said track switch by said operating means when said directional stick relay is deenergized, a signal for governing traffic in the opposite direction over said track section, and means preventing said signal from displaying a proceed indication when said directional stick relay is deenergized.
15. In an interlocking system for railroads, a section of railway track, one signal governing traffic in one direction over said track section, another signal governing traffic in an opposite 45 direction over said track section, a plurality of track circuits located between said signals and including said railway track, two normally energized directional stick relays associated with each of said track circuit said two directional stick 50 relays being for opposite directions, means de-energizing the directional stick relays for a particular direction when the signal for that direction indicates proceed, means maintaining the directional stick relays deenergized for that direction 55 in advance of a train passing through said track section after said train has accepted said signal indicating proceed said means including said track circuits, means causing said directional stick relays for that direction to be reenergized in the 60 rear of said train passing through said track section if said signal for that direction indicates stop, means maintaining the directional stick relays for the opposite direction energized during the passage of said train, means preventing said one and 65 said another signals from indicating proceed at the same time said means including the directional stick relays for the opposing directions respectively, and other traffic controlling means governed by said directional stick relays.
16. In combination, a stretch of railway track, a signal at each end of said stretch each governing movement of traffic into said stretch, a track switch at an intermediate point in said stretch, a route wire extending from one to the other of 70 75

said signals and including a contact closed only if said switch is in a position to establish a route over said stretch and connected at each end to the same terminal of a source of current, a route relay 5 associated with each of said signals for controlling such signal, and manually controllable means for each route relay which normally short-circuits such route relay for connecting that end of the route wire to the opposite terminal of said source 10 and including the associated relay in said route wire.

17. In combination, a stretch of railway track, a signal at each end of said stretch each governing movement of traffic into said stretch, a track 15 switch at an intermediate point in said stretch, a route wire extending from one to the other of said signals and including a contact closed only if said switch is in a position to establish a route over said stretch and connected at each end to the same terminal of a source of current, a route 20 relay associated with each of said signals for controlling such signal, manually controllable means for each route relay for connecting that end of the route wire to the opposite terminal of 25 said source and including the associated relay in said route wire, traffic controlled contacts included in said route wire, and manually operable means for shunting said traffic controlled contacts.

18. In combination; a stretch of railway track; a signal at one end of said stretch governing the entrance of traffic into said stretch from that end by indicating proceed or stop; a signal at the other end of said stretch governing the entrance of traffic into said stretch from that end by indicating proceed or stop; a free and unlockable lever for each of said signals, each of said levers so controlling its respective signal that it may always be caused to indicate stop, but can 40 be caused to indicate proceed only when traffic conditions are proper in said stretch; a time measuring means associated with each of said signals, each of said time measuring means being at times effective, when its respective signal is 45 caused to indicate stop by its lever after indicating proceed, to measure off a predetermined time before the opposite one of said signals can be caused to indicate proceed in accordance with traffic conditions; and manually operable means 50 for at times rendering said time measuring means ineffective.

19. In combination, a stretch of railway track, a signal for governing the movement of traffic into said stretch, said signal being normally incapable of being cleared to allow the passage of 55 traffic when said stretch of track is occupied by a train which entered said stretch from the opposite direction, and manually operable means effective to render said signal controllable independently of traffic conditions.

20. In combination, a stretch of railway track, a signal for governing the movement of traffic into said stretch in one direction, traffic controlled means preventing the clearing of said signal 60 only when said stretch is occupied by a train which entered said stretch from the opposite direction, and manually operable means effective to render said signal controllable independently of said traffic controlled means.

21. In combination, a circuit extending between two traffic governing relays respectively associated with the opposite ends of a section of railway track over which traffic may move in either direction and containing a track switch, a 65 source of current at each end of the circuit for

supplying current to said circuit but normally disconnected therefrom, a manually controlled relay associated with each end of said circuit, means governed by each manually controlled relay when energized to connect the associated current source with said circuit, signals governed by said traffic governing relays to allow traffic to move through the section in a direction determined by the end at which said circuit is supplied with current, contacts in said circuit assuming a position in accordance with the position assumed by the track switch, power operating means for the track switch, manually controlled means for governing the operation of said power operating means, and means preventing the response of said power operating means to said manually controlled means when said circuit is energized, whereby operation of said manually controlled means while said circuit is energized does not affect the control of said signals. 10 15 20

22. In combination, a circuit extending between two traffic governing relays respectively associated with the opposite ends of a section of railway track over which traffic may move in either direction and containing a track switch, a 25 source of current at each end of the circuit for supplying current to said circuit but normally disconnected therefrom, a manually controlled relay associated with each end of said circuit, means governed by each manually controlled relay when energized to connect the associated current source with said circuit, signals at opposite ends of said section of railway track, circuit means governed by said traffic governing relays for clearing one or the other of said signals to 30 allow traffic to move through the section in a direction determined by the end at which said circuit is supplied with current, contacts in said circuit assuming a position in accordance with the position assumed by the track switch, power operating means for the track switch, manually controlled means for governing the operation of said power operating means, means preventing the response of said power operating means to said manually controlled means when said circuit is energized, and means allowing the response of said power operating means to said manually controlled means following the deenergization of said circuit only a predetermined time thereafter if a train is approaching the track switch, whereby operation of said manually controlled means while said circuit is energized does not affect the control of said signals, and whereby the operation of the track switch is at times delayed following the deenergization of said circuit. 35 40 45 50 55

23. In combination, a circuit extending between two traffic governing relays respectively associated with the opposite ends of a section of railway track over which traffic may move in either direction and containing a track switch, a 60 source of current at each end of the circuit for supplying current to said circuit but normally disconnected therefrom, a manually controlled relay associated with each end of said circuit, means governed by each manually controlled relay when energized to connect the associated current source with said circuit, signals governed by said traffic governing relays to allow traffic to move through the section in a direction determined by the end at which said circuit is supplied with current, contacts in said circuit assuming a position in accordance with the position assumed by the track switch, a switch machine for operating the track switch, a manually operable control lever for controlling said switch 65 70 75

machine, and means causing said switch machine to respond to said control lever only if said control lever is manually operated while said circuit is deenergized.

5 24. In an interlocking system for railroads, a railroad track switch, a switch machine for operating said track switch, a free and unlockable lever for controlling said switch machine, a signal for governing traffic over said track switch, 10 a signal lever operable manually to cause said signal to indicate clear or stop, approach locking means preventing operation of said switch machine in response to a change in the position of said first mentioned lever if said signal indicates 15 clear, releasing means for releasing said approach locking means a predetermined time after said signal is manually caused to indicate stop whenever a train is approaching said track switch, means automatically causing said signal 20 to indicate stop upon the passage of a train over said track switch independently of said signal lever, and other means for immediately releasing said approach locking means when said signal is caused to be automatically put to stop, said other 25 means being effective continuously until said signal lever is again manually governed to its stop position.

25. In a relay interlocking system for railroads, two opposing signals at opposite ends of a stretch 30 of single track, a manually controlled relay for each signal; a control circuit for each signal closed only when the manually controlled relay for such signal is energized, the manually controlled relay for the opposing signal is deenergized, and the opposing signal is in its stop position; and approach locking means adjacent each signal and effective when said signal is put to stop by the operation of one or the other of said 35 manually controlled relays, to prevent the clearing of the opposing signal until the first signal has been in the stop position for a predetermined time interval provided a train was approaching said first signal within a predetermined distance when it assumed the stop position.

40 45 26. In an interlocking system for railroads, a stretch of railway track, signals for governing the movement of traffic in both directions into said stretch, manually operable control levers for said signals respectively, interlocking control 50 means responsive to the operation of each lever for clearing the corresponding signal, said interlocking control means allowing said signals to be cleared for only one direction at a time in response to said control levers, and other 55 manually operable means effective to render said signals controllable by their respective control levers independently of said interlocking control means.

55 60 27. In a controlling system for railroads, a stretch of railway track, signals for governing the movement of traffic in both directions into said stretch, manually operable means for each of said signals, circuit means controllable by said 65 manually operable means for said signals for clearing a signal for one direction or the other but incapable of changing the direction of traffic by clearing the opposite signal when said stretch is occupied by a train, and other means rendered effective by manual actuation for allowing said 70 manually operable means to clear a signal for

either direction independently of the occupied condition of said stretch.

28. In an interlocking system for railroads, a stretch of track including a plurality of track switches having power operated switch machines, 5 signals for governing traffic in each direction over said stretch of track, circuit means for clearing a signal for one direction or the other, said means preventing the clearing of said signals governing traffic in one direction when said 10 signals governing traffic in the opposite direction over said stretch are cleared, and said means being effective when a train has accepted such a cleared signal to prevent the clearing of a signal for an opposite direction until the passage of the 15 train out of said stretch, and means for locking said switches in said stretch after said signals for one direction have been cleared and remaining effective even though such signals are returned to stop when a train is in the stretch, said means 20 releasing each of said switches as a train passes beyond each of said switches, whereby the track switches in the rear of a train passing through the stretch may be employed in conflicting routes although the train has not completely passed 25 out of said stretch.

29. In combination, a stretch of railway track, a signal at one end of said stretch governing the entrance of traffic into said stretch at that end by indicating proceed or stop, a signal at the 30 other end of said stretch governing the entrance of traffic into said stretch at that end by indicating proceed or stop, a free and non-lockable lever for each of said signals, each of said levers so controlling its respective signal that it may 35 always be caused to indicate stop but can be caused to indicate proceed only when traffic conditions are proper in said stretch, means including a power-operated time measuring device automatically rendered effective only when a given 40 one of said signals is cleared at a time when an approach track section for such signal is occupied for preventing the clearing of an opposing signal until after a predetermined time, and means for automatically setting said time measuring device into operation to measure said predetermined time when its signal assumes a stop 45 indication after having indicated clear.

30. In combination, a stretch of railway track, a signal at one end of said stretch governing the 50 entrance of traffic into said stretch at that end by indicating proceed or stop, a signal at the other end of said stretch governing the entrance of traffic into said stretch at that end by indicating proceed or stop, a free and non-lockable 55 lever for each of said signals, each of said levers so controlling its respective signal that it may always be caused to indicate stop but can be caused to indicate proceed only when traffic conditions are proper in said stretch, and means including an electrically operable time element rendered effective when its signal is caused to indicate proceed, for preventing clearing of the opposing signal until after said time element device has operated for a predetermined time, and 60 means for automatically initiating the operation of said time element device to measure said predetermined time as soon as its signal is caused to indicate stop by its lever after having indicated proceed.
